FIG. 1 is a perspective view of an adapter showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a bottom rear left perspective view thereof; and,

FIG. 9 is a top rear right perspective view thereof.

The broken lines depicted in the foregoing figures are for purposes of illustration only, and form no part of the claimed design.
